COMBINED BOTTLE AND CAP THEREFOR

Donald George Watt, Toronto, Ontario, Canada, assignor
to Societe d'Assistance Technique pour Produits Nestle
S.A., Lausanne, Switzerland

Filed Mar. 2, 1973, Ser. No. 337,673

Term of patent 14 years

Int. Cl. D9—01

U.S. Cl. D9—117

FIG. 2

FIG. 1

FIG. 4

FIG. 3

FIG. 1 is an elevational view of a combined bottle and cap therefor, embodying my new design, the sides not shown being the same in appearance as the side shown;

FIG. 2 is a top plan view thereof;

FIG. 3 is a bottom plan view thereof; and

FIG. 4 is a sectional view taken along line 4—4 of FIG. 1.

I claim:

The ornamental design for a combined bottle and cap therefor, as shown and described.
